L. B. DECKER

RECOVERY APPARATUS

Filed Aug. 21, 1922.

*Inventor
Lement B. Decker*

*By William Clinton
Attorney*

UNITED STATES PATENT OFFICE.

LEMUEL B. DECKER, OF KENOGAMI, QUEBEC, CANADA.

RECOVERY APPARATUS.

Application filed August 21, 1922. Serial No. 583,409.

To all whom it may concern:

Be it known that I, LEMUEL B. DECKER, a citizen of the United States of America, residing at Kenogami, Province of Quebec, Canada, have invented certain new and useful Improvements in Recovery Apparatus; and I do hereby declare that the following is a full, clear, and exact description of the invention, such as will enable others skilled in the art to which it appertains to make and use the same.

The present invention relates to a recovering apparatus applicable in the various industries, and is designed especially for the recovery of sulphur dioxide gas, relief liquor and heat in the process of cooking wood.

The invention is employed in connection with two or more digesters connected in such a manner that the gases created in one of them may be conducted into the other for use in a subsequent operation of the latter digester. Likewise there is an effective transfer of heat from one digester to the next one during the successive operations, as a result of which the apparatus recovers and conserves heat energy that would otherwise be wasted in the ordinary cooling system.

An additional feature of the invention resides in a means whereby all the digesters of the system are connected to an acid storage tank into which the gases given off may be conducted as desired.

In addition to the foregoing, it has been found in practice that the apparatus gives use to a greater yield of No. 1 pulp per digester as well as a more uniform and better quality of stock.

Further objects and advantages of the invention will appear as the description continues, while others will be particularly pointed out.

The invention is fully disclosed in the following description and in the accompanying drawing, in which like reference characters designate corresponding parts throughout.

The device consists of a pair of digesters indicated as No. 1 and No. 2 respectively. The lower end of each digester carries a cross coupling 1 into the lower openings of which is fitted a cross pipe 2 placing the digesters into communication at their lower ends. One of the lateral branches of each cross receives an acid supply pipe 3, properly fitted with valves or the like (not shown) for controlling the flow of acid thereto.

These pipes 3 may also be joined to a suitable steam supply as is already known in the art. The remaining lateral branch of each cross receives a discharge pipe 4 which communicates with a blowpit.

Each digester is provided at its top with an outlet pipe 5 communicating with the lead-off pipe B by means of the branches 6-7. The lead-off pipe extends to an acid storage tank (not shown). The outlets 5 are controlled by means of valves 8 and 9 fitted in the junctions between these pipes and the branches 6-7. A cross pipe 10 joins the two branches and communicates with the cross pipe 2 by means of a by-pass A connected into the intermediate portions of these pipes. The two sides of the cross pipe 2 are controlled by suitable valves 11 and 12, while opposite sides of the cross pipe 10 are provided with valves 13-14. Similarly the portions of the branches 6-7 rearward of the cross pipe 10 are fitted with the valves 15-16. The digesters may be equipped with gauges 17 for an obvious purpose if desired.

In operation, digester No. 1 is filled with chips and acid in the usual manner. Digester No. 2 is then filled with chips and $\frac{3}{4}$ full of acid. Steam is introduced into No. 1, thus raising the interior to the desired pressure in the usual manner. The valves 9, 14 and 11 are opened, the remaining valves being closed whereby hot acid and gas pass from digester No. 1 into the bottom of No. 2 through branch 7, pipe A and cross pipe 2. Valves 8 and 15 are now opened, valve 13 being kept closed, thus allowing the gas rising from digester No. 2 to flow into the lead-off pipe B and to the storage tank.

When the cooking process in digester No. 1 is finished, valves 9 and 12 are closed so that the product may be blown out through the discharge pipe 4. Valves 9, 14 and 11 are now closed, and the digester is filled with chips and a $\frac{3}{4}$ charge of acid instead of a full charge as in the previous instance. Digester No. 2 is brought to the proper pressure with steam through pipe 3. Valves 8, 13 and 12 are opened, valve 15 being closed, to allow the hot acid to enter the by-pass A, whence the acid gas enters the bottom of digester No. 1 for completing the acid charge therein. Valves 9 and 16 are now opened to allow the gases rising from digester No. 1 to flow to the acid storage tank. When the cooking process in digester No. 2 has been completed, the contents are blown

off, and the operation may be repeated in the manner described.

Although a specific form of the invention has been illustrated and described, it will be understood that various alterations in the details of construction may be made without departing from the spirit of the invention as indicated by the appended claims.

Having thus fully described the invention, 10 what I claim as new and desire to protect by Letters Patent is:—

1. A recovery apparatus comprising a pair of digesters, a cross pipe placing said digesters in communication, means for supplying acid to said digesters, an outlet pipe fitted with each digester, an acid lead-off pipe, branches, connecting said pipe with each of the outlets, a cross pipe connecting said pipe with each of the outlets, a cross pipe 15 connecting said branches, a by-pass connect-

ing the intermediate portions of the cross pipes, and valves arranged in said cross pipes, at opposite sides of the by-pass and in the outlets.

2. A recovery apparatus comprising a pair 25 of digesters, cross couplings fitted at the lower ends of said digesters, a cross pipe connecting said cross supply and discharge pipes fitted into said crosses, an outlet pipe provided in each digester, an acid lead-off pipe, branches connecting said lead-off pipe with the outlets, a cross pipe connecting said branches, a by-pass connecting intermediate portions of said cross pipes, valves fitted in said cross pipes at opposite sides of the 30 by-pass, and in the outlets and branches.

In witness whereof I have hereunto set my hand.

LEMUEL B. DECKER.
